CLAIM

The ornamental design for a travel backpack, as shown and described.

DESCRIPTION

FIG. 1 is a front perspective view of the travel backpack showing my new design;

FIG. 2 is a rear perspective view thereof;

FIG. 3 is a front plan view thereof;

FIG. 4 is a rear plan view thereof;

FIG. 5 is a left side plan view thereof;

FIG. 6 is a right side plan view thereof;

FIG. 7 is a top plan view thereof;

FIG. 8 is a bottom plan view thereof; and,

FIG. 9 is a partial enlarged view of FIG. 2 thereof.

The broken lines depict portions of the travel backpack that form no part of the claimed design.

The long dash-dot broken lines in FIGS. 2 and 9 represent the bounds of the enlargement indications taken from FIG. 2 and forms no part of the claimed design.

1 Claim, 9 Drawing Sheets
